UNITED STATES PATENT OFFICE.

EDWARD A. GUTERMANN, OF MERIDEN, CONNECTICUT, ASSIGNOR TO MANNING, BOWMAN & COMPANY, OF MERIDEN, CONNECTICUT, A CORPORATION OF CONNECTICUT.

DESIGN FOR A LEG FOR CHAFING-DISHES, PERCOLATORS, OR SIMILAR ARTICLES.

40,522.

Specification for Design.

Patented Feb. 22, 1910.

Application filed October 12, 1908. Serial No. 457,450. Term of patent 7 years.

To all whom it may concern:

Be it known that I, EDWARD A. GUTERMANN, a citizen of the United States, residing at Meriden, county of New Haven, State of Connecticut, have invented a new, original, and ornamental Design for a Leg for Chafing-Dishes, Percolators, or Similar Articles, of which the following is a specification.

My invention relates to a new, original and ornamental design for a leg for chafing dishes, percolators, or similar articles.

In the accompanying drawings, Figure 1 is a side elevation of my new and ornamental leg. Fig. 2 is a front elevation thereof.

The design comprises a leg widest at its top and narrowest at its lower end, tapering gradually downward and having the bulged convexed elongated center portion or panel 1 having concaves or grooves along opposite edges, as indicated at 2-2. At the upper wider end of the leg oppositely faced scrolls

3-3 appear terminating at their lower ends in the pendants 4-4. The foot, when viewed in side elevation, curves forward and terminates in the semi-bulbous enlargement 5, while the top, when viewed in side elevation, curves rearwardly.

The salient feature of the design is the artistic effect produced by the double curve last described, together with the elongated and tapered central panel convexed throughout its length, and the simple oppositely faced scrolls at the upper end terminating in the pendant points or ends.

I claim—

The ornamental design for a leg for chafing dishes, percolators or similar articles, as shown and described.

EDWARD A. GUTERMANN.
